UNITED STATES PATENT OFFICE.

SAMUEL LIPPERT, OF CLEVELAND, OHIO, ASSIGNOR OF ONE-HALF TO
JOSEPH SCHAUWEKER, OF CLEVELAND, OHIO.

SCREW-CUTTING DEVICE.

No. 838,344.

Specification of Letters Patent.

Patented Dec. 11, 1906.

Application filed July 28, 1905. Serial No. 271,711.

To all whom it may concern:

Be it known that I, SAMUEL LIPPERT, a citizen of the United States, and a resident of Cleveland, county of Cuyahoga, State of Ohio, have invented certain new and useful Improvements in Screw-Cutting Devices, of which I hereby declare the following to be a full, clear, and exact description, such as will enable others skilled in the art to which it applies to make and use the same.

The invention has for its objects to provide a screw-threading device in which the cutting-dies can be arranged to cut a number of screw-threads of different pitch and size of threads without removal from their case or handle containing them, this making a serviceable tool, light and convenient for general use. I accomplish these objects by means of rotatable cutter-dies, each provided with a plural number of cutting-surfaces. The several surfaces of the dies are provided with cutting screw-threads, and the screw-threads vary in pitch and number of threads to the inch, so that as many dies are provided and as many kinds of screw-threads can be cut therewith as there are cutting-faces or sides to the dies.

The invention consists in the portable case provided with handles and having rotatable or roller dies pivoted in the case. These roller-dies are polygonal, and each side or face is provided with a screw-cutting die, so that a plural number of dies is obtained thereby.

The invention further consists in the guide adapted to support the work while passing through the dies, in means for securing the dies from turning while operating in the work, and in means for adjusting the guides to inclose work of varying diameters and to make the adjustment of the guides relative to the size of the piece to be operated upon coincident with the movement of the rotatable dies, so that when the dies are adjusted to cut a screw-thread upon a piece or rod of given diameter the guides will be also adjusted to clamp upon it and secure it from irregular movement.

The invention further consists in the combination and arrangement of parts, as herein-after described, shown in the above drawings, and specifically pointed out in the claims.

In the accompanying drawings, Figure 1 is

a face view of the device, showing the guides in position and the bar which secures the dies from movement. Fig. 2 is an edge view of the same. Fig. 3 is a transverse section of the device, taken on line *a a*, Fig. 1, and on center line of one of the roller-dies. Fig. 4 is a similar section, taken on line *b b*, Fig. 1, through one of the pins which support the bar and interlocks with the axial pins of the dies and prevents them from moving. Fig. 5 is a longitudinal section through Fig. 1, showing guides for the work and the cams upon the axial pins of the dies, which serves to adjust the distance between the guides to correspond with the diameter of the work to be cut. Fig. 6 is an enlarged end view of the roller-die, showing grooves in the end of the axial pin in which the edge of the retaining-bar enters.

In these views, 1 is the case, having a handle 2 at each end. This case is provided with an opening 3 in the center, in which the roller-dies 4 are pivoted upon axial pins 5. The dies are shown to be octagonal, and in each face are sunk the cutting-teeth of a predetermined pitch and number to the inch, thus affording eight cutting-faces adapted to cut eight varieties of screw-thread. These dies can be turned by hand to present the required corresponding faces together, and the axial pins are provided each with diametrical grooves 6 at one end, so arranged as to locate the position of the cutters and secure them from movement as soon as the retaining-bar 7 is inserted in one of them. This bar is shown to be provided with an edge 8, adapted to enter the grooves in the two adjoining axial pins when they are in alinement. The bar is secured to two pins 8', which extend through transverse openings 9 in the case, and provided with nuts 10 at their outer ends, which enter the enlarged portions 11 of the openings 9. Springs 12 press against the nuts, and by pushing against the nuts the bar can be liberated from the grooves in the axial pins. The nuts serve to retain the bar in place and also can be adjusted to give exactly the right tension to make the operation of the bar most convenient. The guides 13 are adapted to hold the work while being acted upon by the dies.

A device is shown in Figs. 1, 3, and 5 for adjusting the space between the guides simultaneously with turning the dies to pre-

sent new faces to the work, since a screw of small diameter requires a finer screw-thread than one of a larger diameter. Hence the guides should be closer together when a small rod is to be cut than for a rod of large diameter. To accomplish this result, the guides are provided with inwardly-extending lugs or arms 14 and the axial pins of the die-rollers with cams 15, so that as the axes turn the cams will move the guides longitudinally upon the case and open and close them to correspond with the cutters presented to the work. Slots 16 in the guides and screws 17 serve to clamp the guides where desired.

Having described my invention, what I claim as new, and desire to secure by Letters Patent, is—

1. In a screw-cutting device, the combination with a suitable case, of rotatable dies mounted therein, each die being provided with a plural number of cutting-faces, axial pins in said case upon which said dies are secured, diametrical grooves in one end of each pin, a spring-actuated bar adapted to engage

with the aligned grooves of said axial pins, ²⁵ guides arranged to hold the work while operated upon, and mechanism controlled by the movement of said axial pins, for adjusting the opening between the guides, substantially as described. ³⁰

2. In a screw-cutting device, the combination with a case provided with an opening, of cutting-dies pivoted in said opening, and provided with a plural number of cutting-faces, axial pins therefor, guides slidably movable ³⁵ upon said case, and adapted to receive the work acted upon by said dies, the said guides being provided with inwardly - extending lugs, and cams on the axial pins adapted to engage said lugs and to adjust said guides to ⁴⁰ the work relatively to the character of the cutting-faces, substantially as described.

In testimony whereof I hereunto set my hand this 15th day of July, 1905.

SAMUEL LIPPERT.
